UNITED STATES PATENT OFFICE.

WILLIAM FISH AND ISAAC DEETER, OF PLEASANT HILL, OHIO.

TOOL-HOLDER.

SPECIFICATION forming part of Letters Patent No. 361,155, dated April 12, 1887.

Application filed October 30, 1886. Serial No. 217,553. (No model.)

To all whom it may concern:

Be it known that we, WILLIAM FISH and ISAAC DEETER, citizens of the United States, residing at Pleasant Hill, in the county of 5 Miami and State of Ohio, have invented certain new and useful Improvements in Tool-Holders; and we do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 The invention will first be described in connection with the drawings, and then pointed out in the claims.

Figure 1 of the drawings is an elevation in perspective of our tool-stock; Fig. 2, a transverse section, and Fig. 3 a group of detail views. Fig. 4 is a perspective view of the rotating core.

In the drawings, A represents a shell or tube which has one or more longitudinal slots, 25 *a*, and, if preferred, the cross-slots *a'*. The slots *a* are open at one end of tube where the bore is large, and closed at the end where the bore is small, comparatively, while the cross-slots *a'* open into the slot *a*. By this construction 30 a bit for drill or screw-driver B may be provided with a screw, *b*, working in a transverse hole surrounded by a thread and kept always in place. It is entered at the open end of slot *a*, passed down until the bit projects to the desired extent from the small 35 hole, and then tightened to hold the bit fast. By simply loosening the screw the reverse operation of removing the bit is accomplished. The shank of screw may be moved into the 40 cross-slots.

At the small end of tube A we use a countersinking-tool, C, which may be integral therewith or screwed into position.

D is an end plug provided at one end with 45 the round head *d*, having a set-screw, *d'*, which passes through slot *a* and clamps it to the tube, and at the other end it has a tapering head, *d''*, which is not round, but of a preferably angular cross-section, and cross-notched 50 at *d''* to receive the point of a clamp-screw, *d''*,

which retains it in the hole *e* of an ordinary handle, E.

F represents a scale by which the bit may be adjusted.

In Fig. 4 of the drawings we show a core, 55 G, which is longitudinally grooved to hold several bits or tools, each groove open in front and closed at the rear. These grooves are so arranged in the core that each may be made to register with the outlet, so that by turning 60 the core any preferred bit may be used, and they may be changed in a few moments. When the core G is used, we make one or more openings, *a''*, near the rear end, so that the core may be first inserted in the tube and the bits 65 or other tools then placed in the grooves. In some kinds of work it will be a great convenience to have our revolving core, while in others it will not be necessary.

Having thus described all that is necessary 70 to a full understanding of our invention, what we claim as new, and desire to protect by Letters Patent, is—

1. The combination, with a handle, E, having the hole *e* and the set-screw *d'*, of the plug 75 D, having an end shaped to fit said hole *e* and provided with cross slots *d''* to receive the end of said screw, as described.

2. The combination, with a set-screw, *d'*, and a tubular tool-stock open at both ends 80 and provided with the longitudinal slot *a*, of a plug, D, having a head fitting the upper hole of said stock, and having a longitudinal slot to receive the point of said screw, whereby the plug is held in the stock without being 85 able to turn therein.

3. An open-ended tubular tool-stock having the longitudinal slot *a* and suitable clamp-screws, in combination with a core longitudinally grooved to receive different tools and 90 adapted to turn in the stock, as and for the purpose specified.

In testimony whereof we affix our signatures in presence of two witnesses.

WILLIAM FISH.
ISAAC DEETER.
